UNITED STATES PATENT OFFICE.

KOSTA R. MILOVANOVITCH-KOKA, OF VIENNA, AUSTRIA-HUNGARY.

MAGAZINE-GUN.

SPECIFICATION forming part of Letters Patent No. 453,303, dated June 2, 1891.

Application filed May 24, 1890. Serial No. 353,284. (No model.)

To all whom it may concern:

Be it known that I, KOSTA R. MILOVANOVITCH-KOKA, colonel and military attaché of the King of Servia, subject of the King of Servia, and residing at Vienna, in the Province of Lower Austria, in the Empire of Austria-Hungary, have invented certain new and useful Improvements in Repeating-Rifles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to the drawings, Figure 1 is a longitudinal sectional elevation of so much of a breech-loading gun embodying my invention as will be necessary to illustrate the same. Fig. 2 is a top plan view, and Fig. 3 a side elevation with part of the receiver broken away. Fig. 4 is a longitudinal axial sectional elevation of the breech-bolt; and Figs. 5 and 6 are top plan views, the handle or actuating portion thereof being shown drawn out in Fig. 6. Fig. 7 is a side elevation, and Fig. 8 a cross-section on line $x-x$ of Fig. 7, of the breech-bolt proper. Fig. 9 shows the breech-bolt head by an end and an under side view, respectively. Fig. 10 shows the handle or actuating piece of the breech-bolt in side elevation and cross-section, respectively, the latter being taken on or about on the line $y-y$ indicated in said side elevation. Fig. 11 shows in end view and side elevation that piece of the breech-bolt to which the firing-pin is connected and that serves to set the said pin to full or half cock. Fig. 12 shows the firing-pin by an end view and a part thereof in side elevation. Fig. 13 is a sectional side elevation of the receiver and magazine and a portion of the gunstock. Figs. 14, 15, and 16 are cross-sections of the magazine and receiver, illustrating the cartridge-locking device in various positions. Fig. 17 is a longitudinal section of the magazine-case, and Fig. 18 is a top plan view of the magazine. Figs. 19, 20, and 21 are detail perspective views of parts of the magazine. Fig. 22 is a perspective view of the handle-piece A of the gun.

The invention relates to that class of breech-loading fire-arms in which the breech-bolt has a longitudinal and partly-rotary movement imparted to it by a pull in a rectilinear direction and known as the "straight-pull breech action;" and it has for its object to simplify the construction of the breech action and increase the strength thereof and to combine with the gun a magazine depending therefrom and opening into the receiver, the cartridges being fed thereto in a straight vertical line by a feed-spring and follower.

The further object of my invention is to provide the magazine with means for holding the cartridges from being moved into the receiver when the breech-bolt is drawn back and with means for moving the cartridge holder or check out of the way and locking the same in that position to adapt the gun for use as a single-loader; also, with means for compressing the feed-spring and for locking the same and the follower against operation for the purpose of facilitating the introduction of the cartridges into the magazine.

To these ends the invention consists in the construction of the breech mechanism, in the combination of the parts thereof, and in the construction of the magazine, as will now be fully described, reference being had to the above-described drawings, in which like letters indicate like parts wherever such may occur in the figures thereof.

A, Fig. 7, is the breech-bolt proper, and is provided with the longitudinal locking-rib a and at its rear end with a helical or spiral groove a' , that is engaged by a correspondingly-formed extension a^2 on the handle-piece A', Fig. 10, said piece carrying the handle a^3 , having the locking-shoulder a^3 . The handle-piece A' is further provided with a prism-shaped guide-rib a^4 , that moves in a corresponding groove b , Figs. 1 and 2, formed in the receiver B, so as to lock said handle-piece against rotation in said receiver when moved to or fro therein in closing or opening the breech and to impart to the breech-bolt A a partial revolution when the spiral extension a^2 moves in the spiral groove a' of the breech-bolt. When these parts are in the position shown in Fig. 6, the breech-bolt can be introduced into the receiver, a shoulder a^7 , Figs. 10 and 22, of the spiral extension a^2 of the

handle-piece A' bearing against the rear end of the breech-bolt A, so that the latter can be pushed forward to close the breech. By continuing the pressure upon the handle-piece A' through the handle a^3 in a forward direction the spiral extension of said handle-piece will move in the spiral groove a^1 of the breech-bolt A and impart to the same a partial rotation toward the right, whereby the locking-rib a is caused to enter a longitudinal recess in the side of said receiver B, the breech-bolt assuming the position shown in Figs. 1, 2, and 5.

In the bore of the handle-piece A' is fitted a piece A², Fig. 11, which constitutes the cock of the firing mechanism and is provided with a rib a^{32} , in which are formed the half and full cock notches a^6 a^7 , respectively, and said piece has a milled flange a^{20} for manipulating the same.

The breech-bolt A, the handle-piece A', and the cock A² are connected together by means of the firing-pin a^5 , whose rear end is screwed into the piece A², said firing-pin having a collar or annular flange a^{45} near its front end, that forms an abutment for one end of the usual coiled spring a^8 on said pin, the other end of which abuts against the rear wall of the enlarged portion of the bore of the breech-bolt, as shown in Fig. 4.

To the front end of the breech-bolt is secured a head, hereinafter referred to as the bolt-head A³, Fig. 9, which has an attenuated extension or shank a^{43} , in which is formed a diametral slot or recess a^{15} , into which fit the locking-lugs a^{16} , Fig. 12, of the firing-pin a^5 , and said extension a^{43} of the bolt-head fits into the bore of the breech-bolt A (see Fig. 4) and forms an abutment for limiting the forward movement of the firing-pin a^5 under the stress of the spring a^8 .

By means of the diametral slot or recess a^{15} , formed in the end of the extension a^{43} of the bolt-head A³, and the radial lugs a^{16} in front of the collar a^{45} on the firing-pin the latter may be held against rotation in screwing the cock A² to or unscrewing it from the firing-pin a^5 . The bolt-head A³ is locked to the breech-bolt by means of a screw a^{13} , that enters a recess in the shank a^{43} of said bolt-head, the said screw serving also to connect the stop-disk a^{12} to the locking-rib a of said bolt.

The bolt-head shank a^{43} and the bolt-head A³ have a longitudinal peripheral groove a^{10} for the reception of the shank of the shell-extractor a^9 , which is thus detachably connected with the breech-bolt and securely locked thereto by the bolt-head, the extractor being suitably bent, as shown, to conform to the difference in the planes of the groove a^{10} in the bolt-head and its shank, as plainly shown in Fig. 4. The bolt and bolt-heads are further locked together by a projection a^{11} on said head engaging a recess a^{41} , formed in the end of the locking-rib a , that projects beyond said breech-bolt, as shown in Figs. 5 and 6.

At its outer end the bolt-head A³ has two

radial locking-lugs a^{14} , adapted to engage corresponding recesses b in the forward end of the receiver B, Figs. 1 and 2, thus adding 70 very materially to the strength of the breech mechanism and its power to resist the recoil of the explosive charge in firing.

I have hereinbefore stated that when the breech-bolt and its component parts are in the position shown in Fig. 6 said breech-bolt may be introduced into the chamber provided therefor in the receiver. It follows that by moving said bolt into the position shown they may be removed from the receiver, and from 80 the description of the means for connecting the parts it will be readily seen that they can be dismembered or disconnected with great facility. This is done by first unscrewing the cock A² from the end of the firing-pin a^5 , 85 then loosening the screw a^{13} sufficiently to permit the withdrawal of the bolt-head A³, when the firing-pin and its spring may also be withdrawn, and as the intermediate piece A', that actuates the breech-bolt, is connected 90 thereto by the firing-pin and the cock A², said piece can be detached immediately after the piece A² has been unscrewed from the firing-pin. The removal of the bolt-head A³ also permits the removal of the shell-extractor a^9 , 95 as will be readily understood.

The parts A A' A² A³, that constitute the breech-bolt, are of such construction as to present no weak points, so that the breech-bolt is substantially as strong as if it were made 100 in one piece, while the locking devices a and a^{14} provided lock it firmly to the receiver. As the breech-bolt is being moved forward to close the breech, the full-cock notch a^7 in the rib a^{33} of the cock A² will engage the sear a^{18} 105 and prevent the cock A² and the firing-pin from advancing with the breech-bolt, thus bringing the spring a^8 under tension to throw the pin forward when pressure is applied to the trigger a^{19} , to which the sear is fulcrumed 110 or pivoted. The sear and trigger are returned into their normal position by the sear-spring a^{64} , Fig. 1, and as shown in said Fig. 1 the trigger has a lever-arm a^{33} , that bears on the under side of the rear tang b^{31} of the receiver 115 to provide the necessary leverage to depress the sear a^{18} .

The gun may be fired by the forward movement of the breech-bolt when this is done with sufficient force to explode the cartridge-primer by locking the sear out of the path of the cock A². To this end I provide a locking lever or latch a^{21} , Fig. 1, that has a notch in its forward end adapted to engage a corresponding shoulder a^{34} on the trigger, said latch being pivoted to the trigger-guard, as shown.

It has hereinbefore been stated that the cock A² has a milled flange or rib a^{20} for the purpose of manipulating said cock. It will 130 readily be seen that the cock may be drawn out for the purpose of setting the same for firing after the breech is closed or for releasing the said cock from the sear or setting

- the same at half-cock by properly manipulating the trigger in conjunction with the cock A². It will also be seen that the breech-bolt as a whole is very short as compared with the breech-bolts in use in this class of fire-arms, and that it is devoid of a groove in that portion which carries the locking-rib, as is usual, so that those parts which are subjected to the greatest strain are in no manner weakened.
- 5 On withdrawing the breech-bolt A to open the breech the spiral extension of the actuating-piece A' operates in the corresponding groove a' of the breech-bolt proper and imparts to said bolt a partial rotation from right to left, thereby disengaging the rib a and the radial locking-shoulders a¹⁴ from their respective recesses, when the breech-bolt is free to move back to its full extent. This backward movement of the breech-bolt is limited
- 10 by an abutment b², Fig. 1, on the receiver, which is in the path of the stop-disk a¹² and arrests the further backward movement of the bolt.
- The gun, as described, may be used as a
- 15 single-loader, or it may be used as a rapid-firing or magazine-gun, to which end the receiver has in its bottom in front of the trigger-guard a slot of such form and dimension as to afford a ready passage to a cartridge inserted from below, a vertical magazine being employed to receive a number of cartridges and feeding devices combined therewith to feed the cartridges one after another to the slot in the receiver.
- 20 The magazine C, Figs. 1 and 13 to 18, inclusive, is substantially of parallelogrammatic form, the forward vertical wall thereof being conical or having the shape of a bullet, as shown in Fig. 17. Around its upper edge is formed a flange c²⁴, by means of which it is secured to the receiver, as shown in Fig. 13. The bottom c of the magazine C is detachably connected with the casing, said bottom having at its front end a lug or lugs c', that take
- 25 into a suitable slot or slots in the forward end wall of said casing, (see Figs. 13 and 17,) while at its rear end said bottom carries an externally-threaded sleeve c², Fig. 1, that is screwed into a nearly-cylindrical recess c⁶, Fig. 17,
- 30 formed in the rear wall of the magazine-casing, said sleeve serving also as a bearing for the lower end of a rod c¹⁹, provided at its upper end with a wedge-shaped block c²⁰, hereinafter referred to as the "spreader-wedge,"
- 35 and for purposes that will presently be explained.
- The cartridges may be supplied to the magazine one by one, or a number of them in the form of a charge may be introduced by the aid of cartridge-holders, each holder carrying a number of cartridges sufficient to fill the magazine. On the other hand, the feeding devices for the cartridges may be locked against operation and the gun used as a single-loader, the cartridges being introduced
- 40 into the receiver from above after the breech-

45 bolt has been moved back to uncover the breech, as shown in Fig. 3.

The feeding devices for feeding the cartridges to the receiver B consist, as usual, of a feed-spring c⁵, to the free end of which is secured a follower c¹². (See Figs. 1, 3, and 18.)

50 In order to prevent the cartridges leaving the magazine under the stress of the feed-spring c⁵ when the receiver is open, I provide a stop C', Fig. 20, consisting of a plate c⁶, that has two L-shaped spring-arms c³ c⁴, and to the back of said plate is secured a sleeve c⁷ for the passage of the screw-rod c¹⁹, Fig. 1, that connects the rear end of the magazine bottom c to the casing, as hereinabove set forth, and that serves as a guide to the spring-stop C', which is movable vertically on the rod c¹⁹.

55 As shown in dotted lines in Fig. 1 and in full lines in Fig. 3, the arms c⁴ extend forward along the shell of the upper cartridge, and the distance between them is such as to allow the rim of the shell to project slightly into the receiver, as shown in Fig. 3. The elastic or spring arms are comparatively short, so that the forward end of the cartridges will be tilted upward, their bullet ends projecting fairly into the receiver. As the breech-bolt is moved forward its head A³ will engage the projecting shell-rim and carry the cartridge along, which cartridge will be pushed fully into the receiver as soon as its rim has passed the end of the spring-arms c⁴ of the stop C', as will be readily understood.

60 At the lower end of the plate c⁶ of the stop C' is secured a plate whose ends project beyond the opposite sides of said plate c⁶, and to said ends are secured milled disks c¹⁰, that lie outside of the magazine-case, the projecting ends c⁹ of the plate lying in a vertical slot c¹¹, on the rear wall of which is formed a stop-shoulder c²², as more plainly shown in Fig. 13.

65 It will be readily seen that when the stop C' is pulled down against the stress of the feed-spring c⁵ and the projecting ends c⁹ moved under the shoulder c²² the cartridges will be locked against upward movement under the stress of said feed-spring, so that the gun can be used as a single-loader. By simply moving the stop from under the locking-shoulder c²² the feed-spring will at once carry the parts into their normal position, the upward movement of the stop being limited by the end of the slot c¹¹, and is locked against downward movement by the locking-shoulder c²².

70 As shown in Fig. 20, the L-shaped spring-arms c³ c⁴ of the stop C' are bent toward each other or inwardly in such manner as to form a V-shaped space above the bend of the arms. When the stop is in its normal position, this bend lies immediately below the spreader-wedge c²⁰, hereinbefore referred to. By moving the spreader-wedge downward between said spring-arms they will be spread apart

and lie along the lateral edges of the slot in the receiver, (see Fig. 14,) thus admitting free passage to the cartridges. The object of these devices is to provide a means whereby the magazine may be emptied by simply spreading the arms of the stop C' and uncovering the receiver, when all the cartridges will be ejected by the feed-spring.

In order to return the spreader-wedge c²⁰ into its normal position, a coiled spring c²¹ is mounted on the rod c⁹, Figs. 1, 3, and 21, between the sleeve c⁷ of the stop C' and the wedge c²⁰.

The rod c¹⁹ and wedge c²⁰ are moved downwardly by the following devices: A cam or eccentric provided with a thumb-piece c¹⁷ is arranged to revolve in the sleeve or tubular nut c², hereinbefore referred to, said eccentric having an inclined face c¹⁸ in contact with the bottom of the magazine, and to said eccentric is pivoted the rod c¹⁹, that carries the spreader-wedge c²⁰. If the cam is turned to the position shown in dotted lines in Fig. 17, the inclined surface will move under the magazine, drawing the rod c¹⁹ down to spread the arms of the stop C', as will be readily understood.

In the description of the construction of the parts of the breech-bolt and their interconnection through the medium of the firing-pin and its spring I provide an elastic connection between these parts, whereby the cock A² and the handle-piece A' may have an independent motion, the head A³ being made removable for the purpose of having access to the chamber that contains the spring which actuates the firing-pin.

As shown in Figs. 3 and 13, the magazine is provided in its opposite sides with a recess c²⁵, at the base of which is formed a semicircular slot or opening c²⁶, Fig. 13. In said recesses is fitted a yoke or U-shaped actuating or draw bar C², Fig. 19, the vertical spring-arms c¹⁴ of which are slotted for the sake of lightness and for the purpose of giving them a greater elasticity. At their upper ends said arms are provided on opposite sides of the slot with a lug c¹⁶, the form of which is substantially that of a quarter of a sphere. The follower c¹², secured to the feed-spring c⁵, has a lug c¹⁸ on each side, which takes into the upper end of the slot of the spring-arms c¹⁴ of the draw-bar C². At its lower end the draw-bar C², which straddles the bottom of the magazine, has on each side a milled button c¹⁵, that serve as thumb-pieces or hand-holds. By pulling down the draw-bar the follower c¹² will also be drawn down, thereby compressing the feed-spring c⁵, and as the lugs c¹⁶ reach the semi-cylindrical slot c²⁶ at the bottom of the recess 60 the spring-arms will expand or spread, owing to their elasticity, the lugs c¹⁶ engaging said slot, thus locking the feed-spring against operation and into its compressed position.

The object of the described arrangement is to admit of the introduction of a charge of cartridges through the receiver without inter-

ference by the feed-spring, so that the magazine may be readily replenished.

In the introduction of the cartridges it is not necessary that the locking or retaining arms c³ c⁴ of the stop C' be spread. These arms being, as stated, more or less elastic will yield to pressure from above and spread, so as to admit of the free passage of the cartridges.

In the description of the magazine C, I have stated that the bottom thereof is detachably connected with such magazine, and as the feed-spring c⁵ is secured to said bottom it is obvious that the said spring can be readily removed when this becomes necessary for any purpose.

Having described my invention, what I claim, and desire to secure by Letters Patent, is—

1. In a breech-loading gun, the combination, with the receiver and the breech-bolt provided at its rear end with a helical or spiral groove, of a handle-piece having rectilinear motion in the receiver and provided with a helical or spiral extension in perpetual engagement with the like groove in the bolt and with a locking-rib in perpetual engagement with a groove in the receiver for locking the handle-piece against rotation, said extension having a shoulder a¹⁷, adapted to engage the rear face of the breech-bolt, as and for the purpose set forth.

2. In a breech-loading gun, the combination, with the receiver, the breech-bolt provided at its rear end with a helical or spiral groove, a spring-actuated firing-pin contained in the bolt, and a cock A², to which the rear end of said firing-pin is secured, of a handle-piece A', having rectilinear motion only in the receiver and provided with a helical or spiral extension a² in perpetual engagement with the like groove in the bolt and with a shoulder a¹⁷, adapted to engage the rear face of the breech-bolt, substantially as and for the purposes set forth.

3. In a breech-loading gun, the combination, with the receiver, the breech-bolt provided at its rear end with a helical or spiral groove, the firing-pin and its spring a⁵, contained within the breech-bolt, the cock A², provided with the full and half cock notches and to which the rear end of the firing-pin is secured, and the spring-actuated sear a¹⁸, projecting into the receiver, of the handle-piece A', provided with a longitudinal rib a⁴ on its under side and with the helical or spiral extension a², having the abutment or shoulder a¹⁷, adapted to engage the rear face of the breech-bolt, said extension being in perpetual engagement with the corresponding groove in the breech-bolt and said rib being in perpetual engagement with a groove in the receiver, substantially as and for the purposes set forth.

4. The combination, with the breech-bolt and the firing-pin provided near its front end with radial lugs a¹⁶, of a bolt-head provided with a tubular extension fitting into the front end of

the breech-bolt, said extension having radial recesses for the reception of the lugs a^{16} , substantially as and for the purposes set forth.

5. The combination, with the breech-bolt 5 the spring-actuated firing-pin provided at its front end with radial lugs a^{16} , and the cock A^2 , into which said firing-pin is screwed, of the bolt-head provided with an extension fitting into the front end of the breech-bolt, said extension having radial recesses for the reception of the lugs a^{16} , substantially as and for the purposes set forth.

6. In a breech-loading gun, a breech-bolt composed of a tubular bolt having its bore 15 enlarged to form a chamber, said bolt having in its rear end a helical or spiral groove, a handle-piece provided with a helical or spiral extension adapted to operate in the corresponding groove of the bolt, a cock provided with a full and half cock notches loosely inserted in the handle-piece, a firing-pin extending axially through the bolt and handle-piece and having its rear end rigidly connected with the cock and provided near 25 its forward end with an abutment or collar, and a coiled spring located within the chamber of the bolt and encompassing the firing-pin, the ends of said spring abutting, respectively, against the rear end of said chamber and against the collar of said pin, substantially as and for the purpose described.

7. In a breech-loading gun, a breech-bolt composed of two parts A and A^3 , the said part A being provided with a longitudinal locking-rib 35 projecting beyond the outer end of said part A and having a recess in its inner face, and said part A^3 being provided with a tubular extension adapted to fit into said outer end of the part A, said tubular extension having a longitudinal groove a^{10} , the lugs a^{14} a^{14} on said part A^3 , adapted to engage the recess in the locking-rib and recesses in the receiver, respectively, and the screw a^{13} , extending through the locking-rib into the 45 longitudinal groove a^{10} , for the purpose set forth.

8. In a breech-loading gun, the combination, with the receiver, the breech-bolt composed of a tubular bolt provided at its rear end 50 with a helical or spiral groove, and a like bolt-head provided with an extension fitting into the front end of the bolt, said extension having in its face radial recesses, of a spring-actuated firing-pin within said bolt, provided 55 near its front end with a collar and with radial lugs in front of said collar, adapted to enter the recesses in the bolt-head, the cock A^2 , to which the rear end of the firing-pin is screwed, and the handle-piece A' , loosely 60 mounted on the cock and provided with a rib a^4 and with a helical or spiral extension a^2 , having an abutment a^{17} , adapted to engage the rear face of the breech-bolt, said extension being in perpetual engagement with the corresponding groove in said breech-bolt and said 65 rib a^4 in perpetual engagement with a groove

in the receiver, substantially as and for the purposes set forth.

9. In a breech-loading gun, the combination, with the bolt A, the firing-pin, and its actuating-spring a^5 , arranged as described, said firing-pin being provided with radial lugs a^{16} of the bolt-head A ^{3} , provided with a diametrical groove in its rear face for the reception of the lugs on the firing-pin, and a locking device for locking the bolt-head to the bolt, substantially as and for the purpose described.

10. In a breech-loading gun, the combination, with the receiver provided in one of its sides with a locking recess or shoulder and at 80 its opposite side with a stop-shoulder b^2 of the breech-bolt provided with a longitudinal rib, and a stop-disk a^{12} , secured to said rib, adapted to respectively engage the locking and stop shoulders of the receiver as the bolt is 85 moving in one or the other direction and is partially rotated during such movement, substantially as and for the purpose described.

11. In a breech-loading gun, the combination, with the breech-bolt A, provided with 90 the locking-rib a , with a helical or spiral groove at its rear end, and with an axial bore, a portion of which is enlarged, of the bolt-head A ^{3} , provided with an extension or shank having a diametral groove in its rear face and 95 fitting into the forward end of the bolt, a handle-piece A', provided with a helical or spiral extension a^3 , adapted to operate in the corresponding groove of the bolt, a cock A ^{2} , having endwise motion in the handle-piece, a firing-pin extending through the handle-piece, bolt, and bolt-head and having its rear end rigidly connected to the cock and provided near its forward end with a collar and with radial lugs a^{16} in front of said collar, said 100 lugs being adapted to engage the diametral groove in the bolt-head, a coiled spring located in the enlarged portion of the bore of the bolt and encompassing the firing-pin, the ends of said spring abutting, respectively, 105 against the collar of the firing-pin and against the rear end of the enlarged portion of the bore of the bolt, a stop-disk a^{12} , and a set-screw a^{13} , extending through said disk and 110 through the rib a , and the bolt for locking 115 the said parts together, substantially as and for the purpose described.

12. In a breech-loading gun, the combination, with the breech-bolt and a bolt-head provided with a shank or extension fitting 120 into the bolt, said bolt-head and its shank being provided with a longitudinal groove a^{10} , of the shell-extractor a^9 , bent, as described, and confined by said bolt in the groove a^{10} of the bolt-head, substantially as and for the 125 purpose described.

13. In a breech-loading gun, the combination, with the receiver provided with a longitudinal slot in its bottom, the breech-bolt having a to-and-fro motion in the receiver, a 130 magazine depending from said receiver, and a feed-spring arranged within the magazine

for feeding the cartridges to the receiver, of elastic and vertically-adjustable stop-arms extending along the mouth of the magazine, substantially as and for the purposes set forth.

5 14. In a breech-loading gun, the combination, with the receiver provided with a longitudinal slot in its bottom, the breech-bolt having a to-and-fro motion in the receiver, a vertical magazine depending from said receiver, and a feed-spring arranged within the magazine for feeding the cartridges to the receiver, of elastic stop-arms extending along the mouth of the magazine at the rear end thereof, said stop-arms being adapted for vertical adjustment in the magazine, and a locking device for locking the arms into position when adjusted, substantially as and for the purpose described.

10 15. In a breech-loading gun, the combination, with the receiver provided with a longitudinal slot in its bottom, the breech-bolt having a to-and-fro motion in the receiver, a vertical magazine depending from said receiver, and a feed-spring arranged within the magazine for feeding the cartridges to the receiver, of elastic arms extending along the mouth of the magazine at the rear end thereof and a vertically-movable spreader adapted to operate on the stop-arms to spread the same for the purpose of affording to the cartridges free access to or egress from the magazine, as described.

15 16. In a breech-loading gun, the combination, with the receiver provided with a longitudinal slot in its bottom, the breech-bolt having a to-and-fro motion in the receiver, a vertical magazine depending from the said receiver, and a feed-spring arranged within the magazine for feeding the cartridges to the receiver, of the elastic stop-arms extending along the mouth of the magazine at the rear end thereof, and a vertically - movable spreader adapted to operate on the stop-arms to spread the same for the purpose of affording to the cartridges free access to or egress from the magazine, and a spring for returning the spreader into its normal position, substantially as and for the purpose described.

20 17. In a breech-loading gun, the combination, with the receiver provided with a longitudinal slot in its bottom, the breech-bolt having a to-and-fro motion in the receiver, a vertical magazine depending from said receiver, and a feed-spring arranged within the magazine for feeding the cartridges to the receiver, of a vertically-adjustable draw-bar connected with the feed end of the spring, and a locking device for locking the bar in position when adjusted, substantially as and for the purpose described.

25 18. The combination, with the magazine

provided in its front wall near the lower edge with a slot or slots, of the magazine bottom provided at its front end with a lug or lugs adapted to engage said slot or slots, and a locking device for detachably locking said bottom of the magazine at its rear end, and a feed-spring secured to said bottom, whereby said bottom and feed-spring may be readily removed from the magazine, as described.

30 19. The combination, with the magazine provided in its rear vertical wall with a recess and a rod or shaft adapted to move vertically in said recess and carrying at its upper end a wedge-shaped block, of connected elastic stop-arms loosely mounted on the rod, said arms extending forwardly along the mouth of the magazine on opposite sides of the block, and a locking device for locking the arms against motion on or with the rod, whereby when said rod is moved down the arms are moved laterally, substantially as and for the purpose described.

35 20. The combination, with the magazine provided with a recess in its rear vertical wall and a rod or shaft adapted to move vertically in said recess and carrying a wedge-shaped block at its upper end, of connected elastic stop-arms extending forwardly along the mouth of the magazine on opposite sides of the block, said stop-arms being mounted on the rod and adapted to have an independent motion thereon, and a locking device to lock said arms into the position to which they are moved, substantially as and for the purpose described.

40 21. The combination, with the magazine, the feed-spring, and the follower, of a draw-bar connected with the follower and having vertical motions in the magazine, and a locking device for locking the draw-bar into the position to which it may be moved, as described, for the purpose specified.

45 22. The combination, with the magazine provided with a recess in each of its lateral sides and with an opening or slot at the bottom of said recess, the feed-spring c^6 , and the follower c^{12} , carried by said feed-spring, of the U-shaped draw-bar C^2 , having the slotted elastic arms c^{14} detachably connected with the follower and provided with locking-lugs near the upper ends, adapted to engage the slot at the bottom of the recesses when said draw-bar is pulled down, substantially as and for the purpose specified.

50 115 In testimony whereof I affix my signature in presence of two witnesses.

KOSTA R. MILOVANOVITCH-KOKA.
